UNITED STATES PATENT OFFICE.

CHARLES FLECK, OF CLEVELAND, OHIO.

ADVERTISING DEVICE.

Application filed January 7, 1921. Serial No. 435,600.

To all whom it may concern:

Be it known that I, CHARLES FLECK, a citizen of the United States, residing at Cleveland, in the county of Cuyahoga and State of Ohio, have invented certain new and useful Improvements in Advertising Devices, of which the following is a specification.

My invention relates to improvements in advertising devices, and more particularly to that class or type in which an apron adapted to carry and display the advertising matter is intermittently moved by means of intermittently actuated rolls, one of which is intermittently revolved to wind up the apron, and the other is thrown out of gear to unwind the apron as carried by the actuating roll a sufficient distance for the display of the successive advertisements on the apron, means being provided for the automatic reversal of the rolls and the consequent direction of travel of the apron when the latter reaches its end.

The primary object of the invention is to provide a generally improved device or apparatus of the class mentioned which will be exceedingly simple in construction, cheap of manufacture and efficient in use.

A further and very important object is the provision of a generally improved motor actuated device which will be entirely automatic in its operation through the provision of an improved construction and arrangement of electrical devices and connections adapted not only to intermittently drive the apron to predetermined positions for the display of the respective advertisements, but provided also with a suitable source of illumination adapted to be energized for the illumination and display of the advertisement when the apron is at rest, and to be de-energized while the apron is moving from one position to another for the display of a successive advertisement.

A further object is the provision of suitable gear and clutch mechanism adapted to intermittently drive the apron and rolls, suitable electric circuits and contact elements being adapted to be energized and de-energized at suitable predetermined positions of the apron for successively actuating and stopping the apron for the display of the advertisements, as well as for automatically reversing the actuating rolls for reversing the direction of travel of the apron.

With the above mentioned and other ends

in view, the invention consists in the novel construction, arrangement and combination of parts, hereinafter described, illustrated in one of its embodiments in the accompanying drawings and particularly pointed out in the appended claims.

Referring to the accompanying drawings, forming a part of this specification, Figure 1 is a rear view of an advertising or exhibiting device constructed in accordance with this invention, the rear wall of the enclosing casing being removed for the purpose of clearer illustration of the parts, the clutch and driving mechanism being in position to carry the apron from left to right as view from the rear.

Fig. 2, a cross sectional view taken on line 2—2 of Fig. 1.

Fig. 3, a horizontal sectional view.

Fig. 4, a fragmentary cross sectional view taken substantially on line 4—4 of Fig. 3.

Fig. 5, a front elevation of the improved roll actuated display apron detached, and illustrating in particular the marginal contact actuating openings for energizing and de-energizing the respective circuits for intermittently actuating the apron and for reversing the latter at the end of its travel.

Fig. 6, a detailed view of one of the apron actuated electric switches for reversing the apron at the end of its travel.

Fig. 7, a cross sectional view through the upper portion of the casing, illustrating an edge view of the switch shown in Fig. 6.

Fig. 8, a diagrammatic view of the electrical connections and clutch actuating solenoids, the arrows indicating the flow of current through the various circuits when the apron is at rest and is displaying an advertisement.

Fig. 9, a similar view of the same as the apron is moved from right to left (as viewed from the rear) for the display of a successive advertisement on the apron, the clutch shift solenoid being energized for holding the left hand clutch in gear and the right hand clutch out of gear.

Fig. 10, a similar view of the same with the right hand reversing switch and clutch shift energized and moved, respectively, for reversing the travel of the apron so that the latter will travel from left to right.

Fig. 11, a similar view showing the parts energized and shifted for causing the apron to travel from right to left.

Similar numerals or reference designate

like parts throughout all the figures of the drawings.

The web or apron 1, adapted to carry a plurality or series of advertisements 1^a, is adapted to be moved horizontally through the medium of a pair of vertically arranged rolls 2, the latter together with the motor and motor driven roll actuating mechanism being preferably mounted in a casing 3, 10 provided at its front with a suitable sight opening 3^a.

The rolls 2, are preferably removably mounted, the lower ends being provided with suitable clutch members (not shown), 15 seated in the hub members 4^a, of the horizontally disposed gears 4 as shown most clearly in Fig. 4 of the drawings. The gears 4, are mounted on suitable forked bearing members on pedestals 5, and the clutch heads of the rolls 2, are held in seated position by means of spring resisted vertically movable bearing heads 6, receiving the bearing trunnions of the upper ends of the rolls, said bearing heads 6, being 20 slidably arranged in the bearing brackets 7, near the top of the casing 3 as shown clearly in Figs. 1, and 2, of the drawing.

As a means of carrying the display portion of the web or apron 1, in a relatively 30 fixed relation to the front of the casing, and particularly the sight opening 3^a, guide rollers 8, are rotatably mounted between bearing members 8^a, arranged between the upper and lower walls of the casing.

As a means of independently driving one 35 roll or the other for carrying the apron in one direction or the other and also throwing out of gear the roll not driven so as to pay out the apron as driven or wound up by 40 the driving roller, independent driving shafts 9, are mounted in suitable bearing blocks 9^a, at their inner ends, and at their outer ends are mounted in the bearing members or pedestals 5, carrying the gears 10, 45 meshing with the gears 4, connected with the rolls 2 through the clutch member above referred to. The outer ends of the driving shafts 9, are provided with beveled gears 10, always in mesh with the bevel gears 4, 50 beneath the rollers 2.

As a means of driving one or the other of the driving shafts 9, a common driving member 11, is rotatably mounted between the shafts 9, said driving member 11, being 55 provided with a toothed member or sprocket wheel 11^a, and being provided on opposite sides with independent insulated solenoids 11^b, terminating in toothed clutch members 11^c, the magnets or solenoids 11^b, 60 being adapted to be energized to move the clutch members 12, on the shafts 9, in connection with the shifting levers and the solenoids hereinafter described.

The solenoids 11^b, are provided with suitable contact rings 11^d, in contact with con-

tact elements or springs 11^e, suitably connected to the electric circuits hereinafter referred to.

As a means of constantly driving the sprocket wheel 11^a, and solenoids 11^b, a 70 driving shaft 13, is mounted in suitable bearings blocks 14, carried, in the present instance, on adjustable posts 15, mounted in bearing brackets 16 as shown most clearly in Figs. 1, 2 and 4 of the drawings. 75

The driving shaft 13, is provided with a worm gear 17, meshing with a worm 18, on a shaft 19, the latter being mounted on a bearing bracket 20, and the shaft 19, being provided with a wheel 21, adapted to be 80 driven by means of a belting 22, driven from a pulley 23, carried on the driving shaft of a suitable motor 24.

The driving shaft 13, is provided with a sprocket wheel 25, the latter being provided with a sprocket chain 26, passing over the sprocket wheel 11^a, and transmitting motion to the driving member 11, and independent solenoids 11^b. 85

As a means of throwing both of the 90 clutches 12, out of mesh with the clutches 11^c, of the solenoids, and also energizing the lights 27, (see Fig. 8) for the display of the advertisement when the apron is at a standstill (being caused by the clutches 95 being thrown out), and also as a means of automatically reversing the travel of the apron when the latter has reached the end of its travel, (see Fig. 10) a second pair of rotatably mounted solenoids 28, are provided, said solenoids 28 being mounted upon a shaft 29, the latter being mounted in bearings 30, and the shaft 29, being adapted to be driven by means of a gear wheel 31, meshing with a pinion 32, the latter being mounted on a shaft 33, and the shaft 33 being mounted in bearings 34, and the shaft 33 being provided with a gear wheel 35, meshing with a pinion 36, at the end of 100 the driving shaft 13. 105

The solenoids 28, when energized, are adapted to attract the armature clutch members 37, and the latter are adapted to co-operate with the movable clutches 12, through the medium of connecting shift levers 38, pivotally carried in bearing brackets 39, on the connecting frame members 40. 110

The solenoids 28, are provided with surrounding contact rings 28^a, and an intermediate contact ring 28^b, provided with contact elements 28^c. 115

The outer contact rings 28^a, are in contact at all times with the contact elements or springs 28^d, communicating with the secondary circuits 41, and the inner contact element 28^b, and lateral points 28^e, are adapted to contact with switches 28^f, of the inner secondary circuits. 120

The contact elements 28^c, of the sole- 125 130

noids, are in such timed relation to the apron operating switches 42, for intermittently actuating the apron in connection with the spaced contact openings 43, in the 5 lower margin of the advertisement carrying apron 1, that the solenoids 28, will be simultaneously energized to throw both clutches 12, out and hold the apron in a stationary position, the lamp circuit 27^a, being also energized, as shown most clearly 10 in Fig. 8 of the drawings.

Along the upper marginal portion of the apron 1, and near the ends thereof, are provided the apron reversing openings 44, 15 which are adapted at one end or the other to make contact through the apron reversing switches 45, having suitable connection with the circuits for reversing the apron, as shown most clearly in Figs. 10 and 11 of 20 the drawings. The various secondary circuits and switches are in suitable connection with a feed wire 47, and return wire 46.

It will also be understood that the upper and lower margins of the apron 1, which 25 contain the openings 44 and 43, co-operating with the switches or contact elements 45 and 42 respectively, are preferably insulated so that proper contact will only be made when the contact elements meet each 30 other through the openings referred to.

In view of the foregoing, it will be understood that the common driving member 11, 35 rotatably mounted between the shafts 9, and provided with the independent insulated solenoids 11^b, is constantly rotated in one direction only (see Fig. 2) and that the shafts 9 are driven through the clutch members 12, adapted to be energized by the solenoids 11^b, on each side in accordance 40 with the direction in which the apron is travelling, both of said clutches, however, being thrown out through the simultaneous action of the solenoids 28, (see Fig. 8) when the contact elements 42, are brought into 45 circuit through the openings 43, in the lower margin of the apron 1, when it is desired to bring the apron to a rest and display the advertisement by energizing the lamps 27, through the lamp circuits 27^a. Upon reference to Fig. 8 of the drawings, it will be seen that both solenoids 28 are energized, the current flowing through the secondary circuits 41 and the lamp circuits 27^a, as indicated by the arrows in Fig. 8, thereby 55 simultaneously energizing the solenoids 28 and holding the clutches 12 out of engagement with the two clutches 11^c, of the solenoids 11 carried by the constantly rotating common driving member 11 which, as above

60 stated, is constantly driven through the geared connections (see Fig. 2) driven by the motor 24. When in this position it will be apparent that the rotation of the solenoids 28, carrying the central ring 28^b provided with the lateral points 28^c, will cause

the latter to move from beneath the inner contact elements 28^e, as shown in Fig. 9 of the drawings, and the switch members 42 being moved apart or out of contact by the intervention of the lower marginal edges of 70 the apron 1, the lamp circuits 27^a will be cut out thereby causing the current to pass through the secondary circuits 41 and thereby energizing the solenoid 28 at the right and the solenoid 11^b at the left so that the 75 right clutch member 12 and shaft 9 is thrown out and the left clutch member 12 is thrown in, thereby rotating the shaft 9 and the attached geared roller 10 from left to right, or clockwise, in the direction indicated by the arrows and carrying the apron from right to left over the guide rollers 8. Such movement from right to left of the apron (as viewed from the rear) will successively and intermittently take place by 80 the movements of the contact elements and solenoids, as above referred to, until the extreme right end of the apron has been reached whereupon the switches or contact elements 45 will meet each other through 85 the opening 44, on the upper marginal edge of the apron whereupon the secondary circuits 41 will be energized to energize the left hand solenoid 28, thereby throwing out the left hand clutch 12 and energizing the 90 right hand solenoid 11^b, (see Fig. 10) thereby throwing into gear or engagement the right hand clutch 12 and thereby reversing the apron by moving the right hand roller 2 in an opposite direction (and likewise the 100 apron 1) to that shown in the arrows in Fig. 10, which indicate the motion of the apron just after the reversing operation.

This motion of the apron from left to right will continue until the extreme left 105 hand end of the apron is reached, whereupon the left hand contact elements 45 will meet and open a circuit through the apron reversing opening 44 at such extreme left hand end of the apron, thereby causing 110 the current to take the direction indicated by the arrows in the secondary circuits as indicated by the arrows in Fig. 11, such action causing the solenoid 11^b at the left hand side to be energized and the solenoid 28 at the right hand side to be likewise energized, so that the clutch 12 at the right is thrown out and the clutch 12 at the left thrown in to cause the apron to reverse and travel from right to left.

Having thus described one of the embodiments of my invention, without having attempted to set forth all the forms in which it may be made, or all the modes of its use, what I claim and desire to secure by Letters 125 Patent, is,—

1. In an advertising device, including vertically arranged detachable rolls carrying an apron, and independent driving shafts for said rolls; of a continuously 130

- rotating driving member including solenoid and armature clutch members, contact elements normally insulated by said apron and adapted to make and break contact at predetermined positions of the latter, electric circuits connecting said contact elements and solenoids, and means for throwing said driving mechanism out of contact with both of said driving shafts to hold said apron in a stationary position and then engaging one or the other of said shafts for continuing the movements of said apron in one direction or the other.
2. In an advertising device, the combination with a pair of vertically arranged detachable rolls and an apron carried by said rolls and provided with regularly spaced contact openings, and apron operated switches adapted to make and break circuit through said openings; of apron reversing openings

near the ends of said apron, apron reversing switches arranged to make and break circuit through said openings, a continuously rotating driving member, solenoids driven by said driving member, electric circuits provided with contact elements adapted to energize and de-energize said solenoids through said openings and switches as said apron is operated, driving shafts for said apron rolls, and movable armature clutches adapted to alternately throw said shafts into and out of engagement with said driving member for intermittently driving said rolls in one direction or the other and for reversing the travel of said apron at the end of its travel.

In testimony whereof I have affixed my signature.

CHARLES FLECK.
